UNITED STATES PATENT OFFICE.

WALTER G. COOLIDGE AND EDWARD HEMBERLE, OF CHICAGO, ILLINOIS.

IMPROVEMENT IN GIRDERS AND COLUMNS.

Specification forming part of Letters Patent No. 152,794, dated July 7, 1874; application filed March 21, 1874.

CASE B.

To all whom it may concern:

Be it known that we, WALTER G. COOLIDGE and EDWARD HEMBERLE, of Chicago, in the county of Cook and State of Illinois, have invented a new and useful Improvement in Wrought-Iron Columns, of which the following is a specification:

Figure 1 is a cross-section of a column formed by one rolled I-beam, and two of the aforesaid plates or bars. Fig. 2 is a cross-section of a column formed by two rolled I-beams, one plain plate, and two of the said new bars. Fig. 3 is a cross-section of a column formed by three I-beams and two of said new bars. 4 is a front view of a column or post for use in bridges, roofs, &c., constructed as represented in Fig. 3. Fig. 5 is a side view of the same.

Similar letters of reference indicate corresponding parts.

The nature of this invention relates to improvements in the construction of wrought-iron columns.

The invention will first be fully described and then pointed out in the claims.

In the drawing, A represents a new form or shape for iron bars for posts or columns, consisting of the plate *a* with ribbed edges *b'*. B represents plates fitting into the trough of the said bar to form thickening-plates at the ends of the columns. C represents rolled I-beams or plate-girders to be combined with plates A in the manner shown. F is a plain plate, straight or tapered, which may be employed between two I-beams, and C' an I-beam, in place of a plain plate, F. *d d'* are pins passing through ends of columns. These

columns may be made by riveting together two bars, A, with one I-beam, C, as shown by Fig. 2; or two bars, A, with two I-beams, C, and one straight or tapered plain plate, F, as shown in Fig. 3; or two of said bars may be united in another form with three I-beams, as shown in Fig. 4.

Diagonal cross bars or braces may be used to connect the two shapes A in place of the I-beam, by having a flange formed on the shapes A, along the middle, and bolting the bars to them. The column, if used in structures with pin connections, will have the small plates B, before mentioned, riveted to the ends. These plates B fill the trough of the bars A, and are to give additional bearing to the pins *d d'*, as shown in Figs. 5 and 6.

The advantages of our wrought-iron column over others known and in use consist of superior strength for a given amount of metal, simplicity and cheapness of construction, and accessibility of all exposed parts for inspection and painting.

Having thus described our invention, we claim as new and desire to secure by Letters Patent—

1. The combination of two bars, A, with one or more I-beams, and a plain plate, F, for columns or posts, substantially as specified.

2. The combination of end plates B with bars A, I-beam C, and a connecting-pin, *d*, substantially as specified.

WALTER G. COOLIDGE.
EDWARD HEMBERLE.
